HORACE BOYD, OF HOKENDAUQUA, PENNSYLVANIA.

METALLIC RAILROAD-TIE.

1,049,985.

Specification of Letters Patent.

Patented Jan. 7, 1913.

Application filed May 24, 1912. Serial No. 699,378.

To all whom it may concern:

Be it known that I, HORACE BOYD, a citizen of the United States, and a resident of Hokendauqua, in the county of Lehigh 5 and State of Pennsylvania, have invented certain new and useful Improvements in Metallic Railroad-Ties, of which the following is a specification.

My invention is an improvement in metallic railroad ties, and has for its object the provision of a simple economical tie of the character specified, having a maximum of strength for the material used, and of special strength at the seat of the 15 rails, and wherein a simple quickly applied and released fastening device is provided for locking the rail to the tie.

In the drawings: Figure 1 is a plan view of a tie constructed in accordance with the 20 invention; Fig. 2 is a partial longitudinal vertical section of the tie; and Fig. 3 is a plan view of one of the fasteners.

The present embodiment of the invention is composed of sheet metal bent to form 25 a base 1, side walls 2, and overlying flanges 3, at the ends of the side walls, the flanges being in the same plane, and parallel with the base 1.

The flanges 3 do not extend entirely across 30 the width of the tie, but are spaced apart at their free edges, as indicated at 4 in Fig. 1. The side walls 2 are cut away intermediate their ends, as indicated at 5, so that the flanges 3 extend only from the 35 ends of the tie to a point slightly within the adjacent rail 6.

The cutaway portion of each side wall extends from near one rail to near the other, and the holding or fastening device 40 for the rails is arranged in the space 4 between the flanges 3. Each of the said devices consists of a plurality of superposed plates 7 and 8, each plate having an overlying flange 9 and 10 respectively at one 45 side edge.

The plate 7 is arranged beneath plate 8, and the flange 9 of plate 7 is at the opposite side edge from the flange 10 of plate 8. The said flanges thus engage opposite 50 edges of the rail base 11. The plate 7 is of greater width than plate 8, and at the side adjacent to flange 10, the said plate 7 is provided with a laterally upwardly extending rib or flange 13. The plate 8 has 55 a laterally extending tongue 14 at the side adjacent to flange 9, and the said flange 9

is slotted transversely, as shown at 15, to permit the passage of the tongue. The tongue 14 is longitudinally slotted, as shown at 16, to receive a wedge or key 17, for 60 clamping the flanges 9 and 10 on the rail base.

The plates 7 and 8 are arranged below the flanges 3 and the overlying flanges 9 and 10 extend upwardly between the adjacent edges of the flanges to engage the rail base.

The flanges 3 are recessed or notched on their inner edges, at the outer side of each rail, as shown at 18, to permit the passage 70 of the rib 13. In applying the fasteners, the plates 7 and 8 are arranged below the flanges 3, and the flanges 9 and 10 are passed upwardly through the space 4. The key 17 at this time is not in place, so that the 75 plates 7 and 8 may be moved to separate flanges 9 and 10, and permit them to be engaged with the opposite edges of the rail base. After the flanges 9 and 10 are engaged with the rail base, the key 17 is 80 passed through the slot 16, and is driven down. The key is tapering as shown, and bears at one side edge against flange 9 and at the other against the outer end of slot 16, thus pressing the flanges 9 and 10 85 toward each other, and clamping them on the rail base. The rail is now locked to the tie, since the plates 7 and 8 are below flanges 3 and the rail above. The rib 13 prevents lateral displacement of the plates 90 7 and 8, in either direction, and the fastener is locked both to the rail and to the tie. The key or wedge 17 is provided with a head 19, for limiting its downward movement, and for engagement by a tool to lift 95 and loosen the key.

I claim:—

1. A metallic railroad tie comprising a sheet of metal bent to form a base, and side walls, each side wall having an inwardly extending flange at each end, the opposite flanges being spaced apart at their inner edges, and fastening devices for holding the rails to the tie, each of the said devices comprising a pair of superposed plates 100 adapted to be arranged below the flanges, each plate having an overlying flange at one side edge extending between the flanges of the tie and engaging the adjacent edge of the rail base, the lowermost plate having 105 a slot for receiving the flange of the other plate, the lowermost plate having an up-

wardly extending rib at the side remote from its overlying flange and the flanges of the tie being notched to permit the passage of the rib, the uppermost plate having 5 a tongue at the edge remote from its flange, the flange of the lower plate having a slot to permit the passage of the tongue, said tongue being longitudinally slotted, and a wedge or key engaging the slot of the 10 tongue to draw the flanges of the plates together.

2. A metallic railroad tie comprising a sheet of metal bent to form a base, and side walls, each side wall having an inwardly 15 extending flange at each end, the opposite flanges being spaced apart at their inner edges, and fastening devices for holding the rails to the tie, each of the said devices comprising a pair of superposed plates adapted 20 to be arranged below the flanges, each plate having an overlying flange at one side edge extending between the flanges of the tie and engaging the adjacent edge of the rail base, the lowermost plate having a slot for receiving the flange of the other plate, the 25 lowermost plate having an upwardly extending rib at the side remote from its overlying flange and the flanges of the tie being notched to permit the passage of the rib, 30 and means in connection with the plates for clamping the flanges on the rail base.

3. A metallic railroad tie comprising a sheet of metal bent to form a base, and side walls, each side wall having an inwardly 35 extending flange at each end, the opposite flanges being spaced apart at their inner edges, and fastening devices for holding the rails to the tie, each of the said devices comprising a pair of superposed plates, each 40 plate having an overlying flange for engaging the edge of a rail base, said flanges being oppositely arranged, means in connection with the plates for clamping the flanges on the rail base, and means on one of the 45 plates for engaging the tie to prevent movement of the plates longitudinal to the tie.

4. In combination with a tie having a tubular portion at each end for receiving a rail and a longitudinal slot in the upper face 50 of each tubular portion, of a fastening device for each rail, each of the said devices comprising a pair of superposed plates, each having an overlying flange at one side edge for engaging the rail base, said flanges being 55 oppositely arranged, the upper plate having a tongue at the side remote from its flange and the lower plate having a slot in its flange for permitting the passage of the tongue, said tongue having a longitudinal slot, and 60 a wedge or key engaging the slot and bearing at one side against the flange of the lower plate, the lower plate having an upwardly extending rib at the edge remote from the tongue, the tie having a transverse 65 slot for receiving the rib, the upper plate

having a slot in its side edge engaged by the flange of the lower plate.

5. In combination with a tie having a tubular portion at each end for receiving a rail and a longitudinal slot in the upper 70 face of each tubular portion, of a fastening device for each rail, each of the said devices comprising a pair of superposed plates, each having an overlying flange at one side edge for engaging the rail base, said flanges being oppositely arranged, the upper plate having a tongue at the side remote from its flange and the lower plate having a slot in its flange for permitting the passage of the tongue, said tongue having a longitudinal 80 slot, and a wedge or key engaging the slot and bearing at one side against the flange of the lower plate, the lower plate having an upwardly extending rib at the edge remote from the tongue, the tie having a transverse 85 slot for receiving the rib.

6. In combination with a tie having a tubular portion at each end for receiving a rail and a longitudinal slot in the upper face of each tubular portion, of a fastening 90 device for each rail, each of the said devices comprising a pair of superposed plates, each having an overlying flange at one side edge for engaging the rail base, said flanges being oppositely arranged, the upper plate having a tongue at the side remote from its flange and the lower plate having a slot in its flange for permitting the passage of the tongue, said tongue having a longitudinal slot, and a wedge or key engaging the slot and bearing 95 at one side against the flange of the lower plate.

7. In combination with a tie having a tubular portion at each end for receiving a rail and a longitudinal slot in the upper 105 face of each tubular portion, of a fastening device for each rail, each of the said devices comprising a pair of superposed plates, each having an overlying flange at one side edge for engaging the rail base, said flanges being oppositely arranged, the upper plate having a tongue at the side remote from its flange and the lower plate having a slot in its flange for permitting the passage of the tongue, and means in connection with 115 the tongue and the other plate for drawing the flanges together on the rail.

8. In combination with a tie having a tubular portion at each end for receiving a rail and a longitudinal slot in the upper 120 face of each tubular portion, of a fastening device for each rail, each of the said devices comprising a pair of superposed plates, each having an overlying flange at one side edge for engaging the rail base, said flanges 125 being oppositely arranged, and means in connection with the plates for drawing the flanges together on the rail.

9. In combination with a tie having a tubular portion at each end for receiving the 130

rail, and a longitudinal slot in each tubular portion, of a fastening device for each rail, each of the said devices consisting of a pair of superposed plates, each having an overlying flange at one side edge for engaging the rail base, said flanges being oppositely arranged, the said plates being adapted to

engage beneath the flanges, and means for securing the plates together.

HORACE BOYD.
